UNITED STATES PATENT OFFICE

WILLIAM H. HARRISON, JR., OF CHICAGO, ILLINOIS, ASSIGNOR TO W. F. HALL PRINTING COMPANY, OF CHICAGO, ILLINOIS, A CORPORATION OF ILLINOIS

TIPPING MACHINE

Application filed June 4, 1928. Serial No. 282,859.

- The invention relates to improvements in tipping machines and has for its primary object the provision of a machine of this character adapted and arranged to associate automatically articles or objects such as portions of a book, or the like, together thereby facilitating the introduction of inserts or the like into a book, or the like, in assembling the same.
- Another object of the invention is the provision of a machine of this character capable of economical production and highly efficient in use.
- Another object of the invention is the provision of a machine of this character provided with automatic means for stopping or interrupting the operation thereof upon failure of any of the parts to operate properly.
- Other objects will appear hereinafter.
- The invention consists in the combinations and arrangements of parts hereinafter described and claimed.
- The invention will be best understood by reference to the accompanying drawings forming a part of this specification and in which—
- Fig. 1 is a partial side view of a machine embodying the invention;
- Fig. 2 is an enlarged partial top plan view taken substantially from the position 2—2 of Fig. 1;
- Fig. 3 is a section taken substantially on line 3—3 of Fig. 2;
- Fig. 4 is a section similar to Fig. 3 but showing the other end of the machine;
- Fig. 5 is an enlarged section taken substantially on line 5—5 of Fig. 1;
- Fig. 6 is an enlarged section taken substantially on line 6—6 of Fig. 1;
- Fig. 7 is an enlarged detail view illustrating automatic stopping mechanism employed in the machine;
- Fig. 8 is an enlarged detail view of a trigger mechanism employed in said stopping mechanism; and
- Fig. 9 is a detail section through one end of a mercury switch employed in the machine, in conjunction with the automatic stopping mechanism.
- The preferable form of construction as
- illustrated in the drawings, comprises a suitable supporting frame 10, rotatably mounted in suitable bearings in which are hollow shafts 15 and 16, secured to which, respectively, are combined feed and pressure drums 17 and 18. Extending into the bores of said shafts, respectively, are pipes 11 and 12, both of which project from said hollow shafts, as best shown in Figs. 1, 3, 4 and 6, and are secured to the frame of the machine so that they will be held stationary. Said pipes 11 and 12 are fitted to the bores of the shafts 17 and 18 so that said shafts will turn freely thereon. The inner ends of said pipes are closed.
- The shaft 15 projects at one side of the machine and secured thereto is a bevel gear 19 which meshes with a bevel gear 20 secured to a vertically disposed counter-shaft 21, to which continuous rotation is imparted from any suitable source of power during operation of the machine. The shafts 15 and 16 carry intermeshing gears 22 and 23 and by means of which the drums 17 and 18 are geared together to be constantly driven in the direction of the arrows on Fig. 4, as will be readily understood.
- The drums 17 and 18 are provided at their peripheries with annular grooves 24 and combined stripper and guide shoes 25 are mounted in the frame 10 to run in said grooves and strip and remove paper articles or objects from the peripheries of said drums and direct said objects between the rollers 26 and the belts or ribbons 27 operated by intermeshing gears 28 from a gear 29 which, in turn, is operated from the gear 22, and whereby, it will be noted, articles or objects fed or passing between the drums 17 and 18 will be stripped or removed therefrom and fed from the machine through the belts or ribbons 27.
- Associated with the drum 17 is a guide table or apron 30 having a plurality of guide fingers 31 arranged over the same as best shown in Figs. 2, 3 and 4, said guide table and fingers being adapted and arranged to guide articles tangentially onto the periphery of the drum 17. Associated with said guide table and fingers is a lower feed roller 32

55

100

carrying a gear 33 and co-operating with an upper feed roller 34 carrying a gear 35 meshing with the gear 33. The roller 34 is mounted on a rocker member 36 pivoted on a transverse shaft 37 and whereby the roller 34 is free to swing upwardly and downwardly slightly so as to be removed from feeding co-operation with the roller 32 without disengaging the gears 33 and 35.

10 A gear 38 meshes with a gear 39 on a shaft 40 carrying a beveled gear 41 meshing with a beveled gear 42 on a vertical countershaft 43 constantly driven as part and parcel of the normal operation of the machine as will 15 be readily understood. By this arrangement, it will be noted that shaft 40 will be constantly driven and thereby the feed rollers 32 and 34 will also be constantly driven to cause feeding of objects or articles along 20 the top of the table 30 and below the guide fingers 31, as will be readily understood.

A stack of objects or articles, such as book signatures 44 are arranged in a substantially edgewise position in a suitable hopper or receptacle, as best shown in Figs. 1 and 3. Co-operating with the objects 44 is an oscillatory suction arm 45 adapted and arranged to bend down the upper end of the lowermost of the objects 44 and direct it between the 30 feed roller 46 and the notched roller or drum 47 on the shaft 40, thereby periodically extracting the lowermost object or signature 44 and directing the same along the feed table 30 to the feed rollers 32 and 34, as will 35 be readily understood by those skilled in this art.

The feed mechanism for removing the signatures singly and directing them to the feed rollers 32 and 34 is an old and well known 40 feeding mechanism for the purpose and requires no further description here beyond the statement that it is constructed and arranged to remove the signatures 44 singly and direct them to the feed rollers 32 and 34 by which 45 said signatures are further fed along the top of the table 30 to the drum 17.

As best shown in Figs. 2 and 6, bifurcated stop fingers 48 are mounted on a rocker shaft 49 immediately above the drum 17, the lower 50 ends of said stop fingers being set in the path of the signatures traveling along the feed table 30 and arranged to stop and position the same for proper removal therefrom by the feed drums 17.

55 At one end, the rocker shaft 49 is provided with a rocker arm 50 connected with a rod 51 operating through a guide 52 and carrying a compression spring 53 as best shown in Fig. 1, said compression spring 53 thus serving 60 to elevate the free end of arm 50 and thus to hold the stop fingers 48 depressed and in operative relation with the feed table 30 to stop and position signatures fed thereover by the rollers 32 and 34, as explained above.

65 The rocker shaft 49 also carries a rocker

arm 54 carrying a set screw 55 resting on top of one arm 56 of a lever pivoted at 56' and which carries a roller 57 riding upon the periphery of the drum 17 and co-operating with cam recesses 58 therein, as best shown in Fig. 3. The other arm 59 of said lever rests under a set screw 60 on an arm 61 secured to the rocker member 36 which is pivoted on shaft 37 and normally held in depressed relation by a tension spring 62, as shown. The arrangement is such that as each signature 44 is fed by the rollers 32 and 34 along the table 30, the roller 57 runs into the corresponding recess 58 thereby dropping therein and depressing the stop fingers 48 into signature stopping positions and elevating the arm 61 to relieve the roller 34 from feeding contact with said signature to prevent buckling of the same and also to release the same for quick removal by the feed drum 17, as will be presently explained. This action of the parts is caused by the fact that the spring 53 normally tends to rock the shaft 49 to cause depression of the fingers 48, the rocker arm 54 and the set screw 55. Set screw 55 resting on the lever arm 56 thus tends to force the roller 57 downwardly and the lever arm 59 upwardly. When one of the cam recesses 58 passes under the roller 57, depression of the arm 56 is permitted, with consequent elevation of the arm 59. Depression of the arm 56 permits of corresponding rocking of the rocker shaft 49, thereby carrying the stop fingers 48 downwardly into the path of the signatures 44 traveling on the table 30. As previously indicated, this movement is accompanied by an upward movement of the lever arm 59 which through set screw 60 and arm 61 raises the feed roller 34 out of cooperative relationship with the feed roller 32 and thereby simultaneously discontinues feed of the signature 44. Thus each signature fed over the table 30 will be automatically stopped and held in definite relation to the drum 17 by means of the fingers 48. 110

The feed drum 17 is provided with two diametric recesses 63, best shown in Fig. 4, and rocker shafts 64 are mounted to traverse said recesses, each of said rocker shafts carrying a plurality of gripper fingers 65 115 adapted and arranged to grip the edges of the signatures held by the stops 48, as explained above.

At one end, the shafts 64 project from the drum 17 and carry rocker arms 66 connected with rods 67 carrying compression springs 68 and adapted and arranged to swing across a dead center and operate to hold said clamping fingers 65 in either their operative or inoperative positions, as will be readily understood. At their other ends, each of the shafts 64 carries a cam head 69 co-operating with a corresponding stop pin 70 on the corresponding end of the drum 17, as best shown in Fig. 3. Each of the cam heads 69 is also 130

provided with cam grooves 71 and 72 cooperating with cam pins 73 and 74 mounted on the frame of the machine. The cam pin 73 is arranged, as shown, to enter the groove 71 of the upcoming cam head 69, indicated in Fig. 3, when said upcoming cam head arrives adjacent the position of the signature then held by the stops 48 and at the proper time to rock the cam head 69 across its dead center and cause the gripper fingers 65 to rise out of the recesses 63 and clamp the presented edge of said signature. As this movement takes place, the roller 57 arrives at the end of the corresponding recess 58 and runs out of the same being elevated by the end of said recess, thereby elevating the set screw 55 and the rocker arm 54 to elevate the stop fingers 48 to release said signature for removal by the fingers 65.

The action of the pin 73 in the slot 71 is to throw the corresponding fingers 65 up out of the corresponding recess 63 to engage the forward edge of the signature held in feeding position by the stops 48 which immediately thereafter raise to release said signature. The continued motion of the drum 17 causes the corresponding rod and spring 67-68 to swing across the dead center so that the spring then holds the fingers 65 in clamping engagement with the signature as it feeds around on the periphery of the drum 17. When the corresponding cam head 69 encounters the pin 74, the slot 72 runs onto said pin and operates to reverse said cam head and shaft 64, as indicated at the right in Fig. 3, thereby swinging the gripper fingers 65 downwardly into the corresponding recess 63 so that said cam fingers will not interfere with the companion feed drum 18. The shaft 11 for the feed drum 17 is provided with a peripheral port 75 to communicate with air passages 76 extending radially through the corresponding shaft 15 and drum 17, said air passages 76 diverging at their outer ends into the ports 77, Fig. 6, in the periphery of said drum. The port 75 is so positioned in the shaft 11 that it opens into the corresponding passage 76 just prior to the release of the corresponding fingers 75, indicated above.

The forward edge of the signature then being carried around upon the periphery of the drum 17 rests over the corresponding ports 77 and the opening of the port 75 places a suction upon the signature, holding the same to the periphery of said drum and thereby taking the place of the gripping action of the fingers 65 which are immediately to be released. In this manner the signatures will be held in proper position on the periphery of the drum while passing between the drums 17 and 18. Thus as each set of gripping fingers arrives at the uppermost position on the drum 17, it automatically engages the signature which is at the time positioned by

the stops 48 and carries said signature around and between the drums 17 and 18 discharging said signature between the belts or ribbons 27, as explained above.

An arm 78 is also mounted on the rocker shaft 49 between the stop fingers 48, said arm carrying a gravity operated trigger or dog 79 pivoted at 80 so as to be overbalanced in normal position with the lower end thereof in the path of the oncoming signatures on table 30, and so that each signature as it arrives at the stops 48 will engage the lower rear edge of and swing the trigger 79 upwardly, as best indicated in Fig. 8. In this position of trigger 79, its rear lower edge registers with the rear lower edges of the stops 48. The arm 78 is secured to the end of a rod 81 passing loosely through a bracket 82 on the shaft 49 and adjustable by means of an adjusting nut 83 threaded thereon and having a swiveled connection with an L-shaped arm 84 on said bracket and whereby the position of the arm 81 and therefore the trigger finger 79 may be nicely adjusted to be held in the position indicated in Fig. 8 by the properly positioned signature 44.

When held in said position, as will be noted, the trigger finger 79 is swung upwardly into the path of the inner end of a laterally extending rod 85 slidably mounted in a bracket on the frame 10 and normally pressed inwardly by means of a compression spring 86, as best shown in Fig. 2.

The outer end of the rod 85 passes loosely through the end of a lever 87 pivoted at 88 and carrying a roller 89 running upon the inner face of a cam disk 90 on the shaft 91 connected by gear 92 with the gear 22 on shaft 15 and whereby said cam plate 90 will be constantly rotated. The cam plate 90 is provided in its inner face with a cam recess 93 set in the path of roller 89 and so that when the roller 89 arrives opposite the recess 93, if the lever 87 and the rod 85 are otherwise free, the rod 85 and lever 87 may move inwardly. The rod 85 is free when the trigger 79 drops out of registration with its inner end. The lever 87 is free when roller 89 registers with cam recess 93. It thus requires the concurrent and simultaneous occurrence of these two circumstances before the rod 85 and lever 87 are free to move inwardly. The lever 87 rests against the inner side of a stop finger 94 secured to the end of the rod 85 and extends downwardly and rests against the outer side of a rocker arm 95 on the upper end of an inclined rocker shaft 96 mounted on the corresponding side of the frame 10, as best shown in Figs. 2 and 7. By this arrangement, when rod 85 moves inwardly, the finger 94 rocks the arm 95 and rocker shaft 96.

The rocker shaft 96 also carries an upwardly and inwardly curved rocker arm 97, best shown in Fig. 2. The upper inner end of the arm 97 is set in the path of a stop lug 98, best

shown in Fig. 9, on a mounting bracket 99 for a mercury well switch member 100 having a quantity of mercury 101 therein. Obviously, inward rocking of shaft 96 throws the inner end of arm 97 downwardly out of engagement with stop lug 98, thereby releasing mercury well 100.

As best shown in Fig. 7, the mercury well 100 is connected with electric wires 102 which 10 lead to the ordinary control box (not shown) of the electric motor which drives the machine, said mercury switch operating in the usual way, as will be readily understood by those skilled in this art, to break the circuit 15 through the driving motor of the machine when the mercury well 100 tilts downwardly.

The arrangement is such that the upper inner end of the arm 97 normally rests behind the stop plug 98 thereby preventing 20 downward rocking or swinging of the mercury well 100 and thereby normally maintaining the circuit for the electric motor of the machine closed. However, when the stop arm 97 is removed as explained above the 25 weight of the mercury well 100 causes it to swing downwardly, thus breaking the electric circuit for the driving motor and stopping the machine.

As has been previously indicated, the rod 30 85 is held from inward movement by the presence of one of the signatures 44 when the recess 93 arrives opposite the roller 89. However, should there fail to be a signature 44 present at the proper time, the roller 89 35 will drop into the recess 93 thus permitting the rod 85 to move inwardly under the influence of spring 86, which movement will carry the arm 95 inwardly and correspondingly rock the rocker shaft 96 and the rocker arm 40 97 to release the stop lug 98 and permit dropping of the mercury well 100, as indicated above.

This dropping of the mercury well 100 will automatically stop the machine whenever, 45 for any cause, a signature 44 fails to feed up against the stops 48 at the proper time during the normal operation of the machine.

As best shown in Figs. 5, 6 and 7, pivoted links 103 and 104 which are in turn connected 50 by a tension spring 105, connect the mercury well 100 with a rocker arm 106 on a rocker shaft 107 extending transversely across the machine and provided at the other side with an operating handle 108, as best shown in 55 Figs. 2 and 6. Another link 109 has a slot and pin connection 110 with the lever 104 and is pivotally connected at 111 with the inner end of the rocker arm 97. By this arrangement, when the mercury well 100 drops, as indicated above, the slot and pin connection 110 permits of such movement, the spring 105 cushioning the fall. When it is desired to 60 reset the automatic stopping mechanism, all that is necessary is to rock the shaft 107 by 65 means of the operating handle 108, where-

upon the parts will be restored to normal position as will be readily understood.

As best shown in Figs. 1, 3 and 4, associated with the drum 17 is an automatic glue applying mechanism comprising a glue trough 112 70 having a gluing roller 113 constituting one side and a portion of the bottom thereof. The roller 113 is mounted on a feed shaft 114 carrying at one end a pawl 115 co-operating with a spring-held ratchet 116 on a pawl arm 117 loose on the shaft 114, as best shown in Fig. 3. The pawl arm 117 is connected by a rod 118 with an eccentric strap 119 operating on an eccentric 120 fixed to one end of the shaft 91. By this arrangement the gluing 80 roller 113 will be constantly rotated by a step by step movement constantly supplying a fresh supply of glue on the periphery thereof, as will be readily understood.

A regulator in the form of a leaf spring 121 is secured in the bottom of the trough 112 to co-operate with the roller 113 to regulate the film of glue on said roller, said regulator being associated with adjusting screws 122 by means of which the same may be adjusted toward and away from said roller to lessen or increase the thickness of the film of glue thereon. A glue arm 123 is mounted on the shaft 91 and carries a felt pad or strip 124 adapted and arranged to contact with the roller 113 and with the forward edge of a signature 44 on the periphery of the drum 17 immediately following the retraction of the corresponding clamping fingers 65. A balance 125 is also mounted on the shaft 91 to balance 95 the weight of the gluing arm 123 and its co-operating parts. The arrangement is such that as each signature 44 is fed around the periphery of the drum 17, a strip of glue is applied to the forward edge thereof for a purpose to be presently described.

The drum 18 which co-operates with the drum 17, as above indicated, is, in all essential respects, substantially a duplicate thereof, and co-operates therewith to feed articles between the two and between the belts or ribbons 27 for discharge from the machine. Associated and co-operating with the drum 18 is another feed table 126 leading thereto and having guide fingers 127 positioned thereabove. Feed rollers 128 are arranged under the table 126 operating through slots therein and co-operating with balls 129 resting on top of said rollers and serving to hold articles or objects on the table 126 in feeding contact with the rollers 128, but permitting of the ready removal of said articles. The rollers 128 are constantly operated in the direction of the arrows indicated in Fig. 4, by a suitable train of gears, as shown. Arranged at the outer end of the table 126 is a pair of feed rollers 130 and 131 driven by the same train of gears and co-operating with a suitable hopper or receptacle 132 containing a stack of articles or objects 133, such as the 130

leaves or pages of a book, to be inserted in conjunction with the signatures 44. The stack of book pages 133 rests upon a vertically moving platform or table 134 and a pneumatic extracting drum 135 is arranged, as shown, in contact with the top of said stack, said extracting drum being provided with suitable pneumatic ports 136. Suitable driving mechanism is provided, as shown, for the extracting drum 135 and suitable connections are arranged for producing suction or a partial vacuum in the ports 136 to periodically extract the uppermost book page 133 and deliver the same between the guides 137 and 138 to the feed rollers 130 and 131, which in turn deliver said page along the top of table 126 to the rollers 128 and the co-operating balls 129.

The extracting drum 135 and the co-operating receptacle 132 are parts of a well known feeding mechanism now in general use and require no further description here beyond the statement that they operate to remove periodically the uppermost book page or leaf 25 from the receptacle 132 and propel the same along the top of the table 126.

As best indicated in Figs. 4, 5 and 6, a rocker shaft 139 similar in all respects to the rocker shaft 49 is associated with the delivery end of the table 126 and the top of the drum 18, said rocker shaft carrying bifurcated stop fingers 140 adapted and arranged to stop and position the pages 133 fed along the top of the table 126.

As best shown in Fig. 3, the rocker shaft 139 carries a rocker arm 141 carrying a set screw 142 contacting with the end of a lever 143 carrying a roller 144 running upon the periphery of the drum 18. The drum 18 is, to all intents and purposes, a duplicate of the drum 17 and the roller 144 is set in the path of the cam recesses 58 in the drum 18 and whereby the stop fingers 140 will be operated in conjunction with the gripper fingers 65 to position and release the book pages 133 when gripped by the fingers 65.

It will be noted that the distance of travel between the point at which the book pages 133 are gripped by the fingers 65 and the point of tangency of the drums 17 and 18 is considerably shorter than the corresponding distance of travel of the signatures 44 on the periphery of the drum 17. For this reason the cam pins 73 and 74 for the drum 18 are positioned somewhat closer together and the port 75' in the hollow shaft 12 is somewhat shorter than the port 75 in the hollow shaft 11. Otherwise the drum 18 is identical with the drum 17 and needs no further description beyond the statement that it operates to feed the book pages 133 into juxtaposition with the signatures 44 so that the book pages will be attached to said signatures by the glue or adhesive applied thereto as explained above and whereby when said signatures are dis-

charged from the machine as explained above, they will have attached thereto the book pages 133 and so that when said signatures are ultimately assembled into the book for which they are intended, the book pages 133 will be associated therewith in said book and be thereby inserted as pages of said book.

A gravity operated trigger finger 145 is mounted on an adjustable bracket 146 on the rocker shaft 139, said trigger finger being set in the path of a laterally extending rod 147, said parts being in all material respects identical with the trigger finger 79 and the rod 85 mounted on the rocker shaft 49 and associated with the drum 17 and for the same purpose.

At its outer end, the rod 147 operates loosely through a lever 148 carrying a roller 149 running upon the periphery of a cam disk 150 on the shaft 91 containing a recess 151 co-operating with said roller and so positioned as to permit movement of the lever 148 in case there is a failure of the feeding apparatus to feed a book page 133 at the proper time just as the lever 87 operates in the case of a similar failure of the feeding of the signatures 44.

The rod 147 carries an arm 152 co-operating with an arm 153 on the shaft 96 and operating to turn the shaft 96 upon such failure of the feed of a book page 133, thereby stopping the machine just as the failure of the feed of a signature 44 stops the machine as explained above. It will thus be noted that in the case of the failure of either of the feeding mechanisms of the machine to operate properly, the machine will be automatically stopped thereby avoiding errors in the books assembled from the signatures threaded by the machine. By this arrangement a simple and effective automatic machine is provided for superposing and attaching together a book signature and a book page to be inserted in a book, or the like, with great speed and accuracy.

The specific form and arrangement of parts is a simple and effective one for the purpose.

While the preferred form of construction for carrying the invention into effect has been illustrated and described, this is capable of variation and modification without departing from the spirit of the invention. It is therefore not desired to limit the patent to the specific arrangement set forth but to include therein also such variations and modifications as fall within the scope of the appended claims.

I claim:

1. A machine of the class described comprising two co-operating feed and pressure drums, and two co-operating feeding mechanisms arranged to feed objects to said drums, said mechanisms being synchronized to cause said objects to pass between said drums si-

- multaneously and be thereby superposed, both of said drums being equipped both with mechanical gripper fingers and suction means for engaging said objects, and means for successively causing the same to engage objects fed to said drums, the relation being such that said objects will be held to the drums by suction only as their advancing edges pass between said drums.
2. A machine of the class described comprising two co-operating adjacent feed and pressure drums; two co-operating feeding mechanisms arranged to feed objects to said drums, said mechanisms being synchronized to cause said objects to pass between said drums simultaneously and be thereby superposed; and means for automatically stopping the machine upon failure of either of said feeding mechanisms to operate.
3. A construction as specified in claim 2, in which said drums are equipped with both mechanical gripper fingers and suction means for engaging said objects; and means for successively employing the same for holding said objects on said drums, the relation being such that said objects will be held to the drums by suction only as their advancing edges pass between said drums.
4. A machine of the class described comprising two co-operating adjacent feed and pressure drums; two co-operating feeding mechanisms arranged to feed objects to said drums, said mechanisms being synchronized to cause said objects to pass between said drums simultaneously and be thereby superposed; automatic adhesive applying means co-operating with one of said mechanisms to apply adhesive to the objects passing therethrough; and means for automatically stopping the machine upon failure of either of said feeding mechanisms to operate.
5. A machine for the purpose specified, comprising a frame, hollow shafts rotatably mounted in bearings in said frame, co-operating drums secured to said shafts, synchronized feeding means for delivering objects to said drums, respectively, stationary hollow members fitted to the bores of said hollow drum-shafts adapted to be connected with air exhausting means, said hollow members, shafts and drums being provided with ports and passageways adapted and arranged to hold objects to said drums by suction and causing them to pass between said drums with parts thereof in contact.
6. A machine as specified in claim 5, in which the drums are equipped with gripper fingers and means for actuating the same adapted to effect engagement and disengagement of said gripper fingers with and from objects fed to said drums, respectively, and to retract said gripper fingers, the relation being such that the gripper fingers will be retracted after the suction means becomes

operative and before the objects pass between the drums.

7. A machine as specified in claim 1, which also comprises means for applying adhesive to one of said objects.

8. A machine as specified in claim 1, which comprises means for automatically stopping the machine upon failure to function of either of the feeding mechanisms.

In witness that I claim the foregoing as my invention, I affix my signature this 28th day of May, A. D. 1928.
